UNITED STATES PATENT OFFICE.

GLENN R. HOFFMAN, OF SPRINGFIELD, ILLINOIS, ASSIGNOR TO HOFFMAN MANUFACTURING COMPANY, OF SPRINGFIELD, ILLINOIS, A CORPORATION OF ILLINOIS.

TRANSMISSION BAND.

Application filed March 5, 1923. Serial No. 622,913.

To all whom it may concern:

Be it known that I, GLENN R. HOFFMAN, a citizen of the United States, residing at Springfield, in the county of Sangamon and 5 State of Illinois, have invented certain new and useful Improvements in Transmission Bands; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to transmission bands, and has for its object to provide improved features of construction in the removable ear which will permit of its application and removable to and from the band 20 for facilitating the removal of the transmission band from the transmission for needed repairs or other purposes and its replacement thereon without interference with the transmission gears, say of the type used in the 25 Ford car or truck. To the accomplishment of the foregoing and such other objects as may hereinafter appear the invention consists in the features hereinafter particularly described and then sought to be clearly defined by the claims, reference being had to 30 the accompanying drawing forming a part hereof, and in which

Figure 1 is a perspective of the removable ear, detached;

35 Figure 2 a perspective of a portion of the transmission band;

Figure 3 a central longitudinal section through the ear and portion of the metallic strap or band and its lining.

40 In the drawing the numeral 1 designates the removable ear of a transmission band, the other ear which is usually permanently attached to one end of the band not being illustrated as it is constructed and applied 45 in the customary manner and therefore need not be illustrated. The removable ear illustrated has its shank portion formed with slots 2 which are enlarged at one end and also formed on its under face at the notched 50 end of the ear with a depending shoulder or member 3. The band to which this ear will be detachably secured comprises a metallic strap or band 4 having a lining 5 of woven fabric or other suitable material, 55 and headed studs 6 projecting from the band

and designed to be passed through the slots 2 of the ear. The end of the band 4 next to the notched end of the ear is formed with a recess 7 designed to receive the shoulder or member 3 when the ear is in set position on the band so that when the band is applied to its drum and the two ends are drawn towards each other by usual means employed for the purpose, the end of the metal strap portion 4 will abut against the shoulder or 60 member 3 and longitudinal slipping of the ear on the band prevented. To apply the ear to the band, the ear is positioned so that the headed studs will pass through the enlargements of the slots 2 and then the ear is 65 slipped in the direction of the free end of the band so as to bring the headed studs into the narrower portions of the slots and the shoulder or member 3 into the recess 7 of the metal strap portion 4 of the band, the engagement of the heads of the studs with the upper face of the shank of the ear tending to prevent the separation or spreading apart of the ear and band, and longitudinal slipping of the ear in one direction prevented by engagement of the studs with the end walls of the narrow portions of the 70 slots, and movement in the other direction 75 prevented by engagement of the shoulder or member 3 with the end of the metal band 80 85 4 where it lies in the recess formed therein. To remove the ear the metal strap or band and its lining is depressed next to the notched end of the ear to disengage the band from the shoulder or member 3 and then the ear is slid endwise to bring the heads of the 90 studs into register with the enlargements of the slots 2 when the ear is slipped from attachment to the band. This construction 95 is simple and efficient and provides for the easy attachment and detachment of the removable ear to the band so that the transmission band may be readily applied to and removed from its drum.

Having described my invention and set forth its merits what I claim is:

1. A transmission band provided with a removable ear formed with a slot having an enlarged end and on its under face next to the notched end of the ear with a depending shoulder, and a band provided with a headed stud to fit in the slot of the ear and having its end bearing against the depending shoulder of the ear when the headed stud is 105 in the narrow portion of the slot in the ear. 110

2. A transmission band provided with a removable ear formed with a slot having an enlarged end and on its under face next to the notched end of the ear with a depending shoulder, and a band provided with a headed stud to fit in the slot of the ear and having a recess in its end adapted to receive the depending shoulder of the ear when the headed stud is in the narrow portion of the slot.
- In testimony whereof I affix my signature in presence of two witnesses.

GLENN R. HOFFMAN.
